UNITED STATES PATENT OFFICE.

NELSON B. CREIGHTON, OF NEW YORK, N. Y.

VALVE.

1,103,944.

Specification of Letters Patent. Patented July 21, 1914.

Application filed April 16, 1912. Serial No. 691,114.

To all whom it may concern:

Be it known that I, NELSON B. CREIGHTON, a citizen of the United States, and a resident of the city of New York, Maspeth, borough 5 of Queens, in the county of Queens and State of New York, have invented a new and Improved Valve, of which the following is a full, clear, and exact description.

The object of the invention is to provide a 10 new and improved valve for use in pipe lines conveying gas, liquids, or other fluids from one place to another, and arranged to normally hold the valve in open position for the passage of the fluid and to allow of releasing the valve from a distant point whenever it is desired to close the valve and to 15 permit the valve to close automatically in case of fire and to hold it locked in closed position.

For the purpose mentioned, use is made of 20 a spring pressed lever which is normally held in raised position by the holding means above mentioned, and an automatic locking device for locking the lever in lowered position after its release from the said holding 25 means and after the valve has been closed.

A practical embodiment of the invention is represented in the accompanying drawings forming a part of this specification, in 30 which similar characters of reference indicate corresponding parts in all the views.

Figure 1 is a sectional side elevation of the valve in open position; Fig. 2 is a similar view of the same in closed position; Fig. 3 35 is an end view of the valve in open position; Fig. 4 is a cross section of the same in closed position; and Fig. 5 is a perspective view of the actuating lever for the valve.

The valve body A is provided with an inlet 40 B, an outlet C, a valve seat D intermediate the said inlet B and the outlet C, and a separate chamber E closed by a cap F having a removable screw plug G in the top. On the valve seat D is adapted to be seated a valve 45 H, the seat D and the valve H being shown in the form of a gate and gate valve, but I do not limit myself to this particular form of a valve. The valve H is mounted to slide up and down on suitable guideways H' arranged on the inside of the body A and extending within the separate chamber E so that when the valve H is in its normal open position it extends up into the separate chamber E, as plainly indicated in Fig. 1. 50 The valve H is provided on top with a stem H² pivotally connected with the free end of

a lever I arranged within the chamber E and fulcrumed at I' in the said chamber. The lever I is provided with a spring seat I², on which is seated the lower end of a coil 55 spring J extending up in the cap F and abutting against the under side of the plug G. When the lever I and with it the valve H are in raised position the spring J is pressed and when the lever I is released the spring 60 forces the lever I downward so as to move the valve H to its seat. The lever I is further provided with an abutment I³ engaged by a lug or arm K projecting from a rock 65 shaft L extending transversely through the chamber E and journaled in the sides thereof, as plainly indicated in Fig. 4. One outer end of the rock shaft L is provided with an annular shoulder L' and a collar L² and on the shoulder L' fits the apertured end N' of 70 an arm N adapted to be secured to the said shoulder and the collar L² by a solder of a low fusing point. The free end of the arm N rests against an abutment O in the form of a link pivoted at O' on the cap F, and the arm N is connected with a rod P leading to a distant point to permit an operator to impart a swinging motion to the arm N for 75 rocking the shaft L so as to move the lug K out from under the abutment I³ thus releasing the lever I and allowing the spring J to swing the lever downward to move the valve H to its seat. In case of a fire the heat melts the fusible solder connecting the arm N with the rock shaft L so that the latter is 80 released and is free to turn to permit the lever I to swing downward into closed position by the action of the spring J thus seating the valve H. The locking bolt Q is mounted to slide in a bolt chamber R formed 85 on the outside of the chamber E and closed at its outer end by a screw cap S (see Fig. 4). A spring T is arranged within the chamber R and presses the bolt Q inward so that when the lever I swings downward it 90 engages the beveled end thereof and forces the bolt outward against the tension of the spring T. When the lever I has passed the inner beveled end of the bolt Q then the spring T returns the bolt and the inner end 95 thereof now extends on top of the lever I so as to hold the same locked in lowermost position. Now in order to unlock the lever I it is necessary to remove the cap S to obtain access to the bolt Q, the outer end Q' of 100 which projects beyond the chamber R and is provided with an opening for engagement 105 110

by a tool to permit of drawing the bolt Q outward whenever it is desired to swing the lever I upward into normal position for re-engagement by the lug K to hold the lever in the raised position.

6 The rock shaft L is provided with a conical collar L³ seated on a seat E' formed on a screw plug E² forming part of the separate chamber E (see Fig. 4), and the shaft L is pressed on by a spring U to hold the collar L³ firmly to its seat E' to prevent leakage of fluid through the plug E². The detail construction of the rock shaft and arms N and link O is practically the same as the similar devices disclosed in the Letters Patent of the United States, granted to myself and Samuel Block on June 4, 1912, and numbered 1,028,681 and 1,028,682.

10 Having thus described my invention, I claim as new and desire to secure by Letters Patent:

1. A device of the class described, comprising a valve, a spring-pressed lever for actuating the valve, supporting means for normally holding the lever raised, and an automatic locking device for locking the lever in place after being released from the said supporting means and after the valve has moved into closed position, consisting of a bolt arranged in the path of movement of the lever.

2. A device of the class described, comprising a valve body having a valve seat, a valve, a lever pivotally connected with the said valve, a spring pressing the said lever and tending to seat the valve on said seat, means for normally holding the lever in raised position and the valve open, and an automatic locking device for locking the lever in place after being released from the holding means and the valve moved to closed position, consisting of a spring controlled bolt movable laterally in the path of movement of the lever.

3. A device of the class described, comprising a valve body having an inlet, an outlet, a separate chamber and a valve seat intermediate the said inlet and outlet, a valve, a lever in the said chamber connected with the said valve, a spring pressing the said lever and tending to seat the valve on said seat, a rock shaft extending through the said chamber and having a lug within the chamber engaging the said lever to hold the latter normally in raised position against the tension of the said spring whereby the valve is held open, means connected to the rock shaft for holding said lug in operative engagement with the lever, and a releasing device connected with said means.

4. A device of the class described, comprising a valve body having an inlet, an outlet, a separate chamber and a valve seat intermediate the said inlet and outlet, a

valve, a lever in the said chamber connected with the said valve, a spring pressing the said lever, and tending to seat the valve on said seat, a rock shaft extending through the said chamber and having a lug within the 70 chamber engaging the said lever to hold the latter normally in raised position against the tension of the said spring, whereby the valve is held open, means connected to the rock shaft for holding said lug in operative 75 engagement with the lever, a releasing device connected with the said means, and a locking device having a spring-pressed bolt adapted to lock the lever when the valve is in closed position.

5. A device of the class described, comprising a valve body having an inlet, an outlet, a separate chamber and a valve seat intermediate the said inlet and outlet, a valve, a lever in the said chamber connected 85 to the valve and provided with a spring seat and an abutment, a spring seated on the said spring seat and under tension while the valve is open, a device for normally holding the valve open comprising a rock shaft extending through the said chamber and having a lug normally engaging the said abutment to hold the lever in raised position, an arm on one outer end of the said rock shaft, fusible solder connecting the said arm with the said rock shaft, and an abutment for the said arm to rest on whereby the lever may be released from the lug when the solder is fused.

6. A device of the class described, comprising a valve body having an inlet, an outlet, a separate chamber and a valve seat intermediate of said inlet and outlet, a valve, a spring pressed lever in the said chamber connected to the said valve and tending to seat the valve on its seat, means for holding the lever normally raised and maintaining the valve in open position, and a spring pressed locking bolt extending into the path of the lowering movement of said lever to lock the lever after being released and when the valve is seated on its seat.

7. A device of the class described, comprising a valve body having an inlet, an outlet, a separate chamber and a valve seat intermediate the said inlet and outlet, a valve, a spring-pressed lever in the said chamber connected to the said valve, and tending to seat the valve on its seat, means for holding the lever normally raised and maintaining the valve in open position, a bolt chamber on the casing having a cap for closing the outer end of the bolt chamber, and a spring-pressed bolt in the said chamber having its inner end projecting into the path of lowering movement of the said lever, the outer end of the bolt projecting beyond the bolt chamber into the said cap.

8. A device of the character described,

comprising a valve body having a valve seat, a valve, a lever pivotally connected with the said valve, a spring pressing the said lever and tending to seat the valve on said seat, means for normally holding the lever and valve in raised position, and a laterally movable spring controlled bolt having a limited movement in the valve body and provided with a beveled end disposed in the path of movement of the said lever when released, whereby the said bolt may engage the

upper face of the lever when it is lowered to close the valve and thus lock the valve in closed position.

In testimony whereof I have signed my 15 name to this specification in the presence of two subscribing witnesses.

NELSON B. CREIGHTON.
